UNITED STATES PATENT OFFICE.

ANDREW J. JOHNSON, OF CLEVELAND, OHIO.

TROLLEY-RETRACTOR.

SPECIFICATION forming part of Letters Patent No. 690,110, dated December 31, 1901.

Application filed October 12, 1901. Serial No. 78,397. (No model.)

To all whom it may concern:

Be it known that I, ANDREW J. JOHNSON, a citizen of the United States, residing at Cleveland, in the county of Cuyahoga and State of Ohio, have invented a certain new and useful Improvement in Trolley-Retractors, of which the following is a full, clear, and exact description, reference being had to the accompanying drawings.

10 My invention relates to an improved trolley-retractor.

The device in which my invention is embodied maintains the trolley-cord in normal tension under the ordinary running conditions—that is to say, so long as the trolley remains in contact with the conductor-wire and however much the distance of said conductor-wire above the track may vary. If, however, the trolley jumps from the conductor-wire, it 20 will be thrown up suddenly by its spring, whereupon my device will act automatically to draw the trolley-pole downward until the trolley is below the planes of the conductor-wire and of the arms or cross-wires by which said 25 conductor-wire is supported.

The invention may be here generalized as consisting of the novel combination of parts shown in the drawings and, hereinafter described for providing the results above referred to, all of which will be pointed out definitely in the claims.

In the drawings, Figure 1 is a rear view of the retractor. Fig. 2 is a side elevation thereof. Fig. 3 is a central longitudinal sectional view. Fig. 4 is a sectional view in the plane indicated by line 4-4 of Fig. 3 looking to the left. Fig. 5 is a sectional view in the plane indicated by line 5-5 of Fig. 3 looking to the right. Fig. 6 is a side elevation of the rear 40 end of a trolley-car having my retractor attached to it, and Fig. 7 is a perspective view of latch K and spring R.

Referring to the parts by letters, A represents a frame by which the movable parts of 45 the device are supported. It consists in the preferred form, as shown, of a plate a, which is intended to be secured in a vertical position to the outer side of the rear dashboard of the trolley-car. It has also two parallel 50 counterpart members a', which when the plate a is secured as described project rearwardly.

B represents a hollow casing which lies be-

tween and is rotatably mounted in said members a' by means of hubs b, which are fitted into circular holes in said members. This 55 casing has a removable end b', which is secured to it in any appropriate manner, as by screws. The hubs b are bored out and receive a shaft C, which shaft after the reel-spring has been wound up, as will be presently explained, is fastened to said casing. The means employed for this purpose consist of a wheel c, fitted upon a projecting square end of said shaft and having one or more pins c', which enter corresponding slots b² in the 60 end of the adjacent hub b. This wheel is held in a position to maintain the engagement of said pins and slots by a screw c², which screws into the end of said shaft, and a washer c³, embracing the screw and lying between its head 65 and said wheel. Within the casing and rotatably mounted upon this shaft is a reel D, having the hollow cylindrical barrel d, (to which the trolley-cord p is fastened and upon which it will be wound.) Within the barrel 70 of this reel is a helical spring H, one end of which is fastened to the shaft C and the other end to the reel. It is obvious that if the rotation of the casing B is prevented and the spring H is put under tension it will automatically rotate the reel, and thereby take up any slack in the trolley-cord due to the lowering of the conductor-wire, but will be turned in 75 the other direction as the elevation of the conductor-wire increases by the superior force of 80 the trolley-spring. Under normal conditions, therefore, this drum and its spring hold the trolley-cord taut by automatically taking it up or permitting it to pay out, as occasion requires.

Extending between and mounted in the two members a' is the shaft E, on which is loosely mounted the hub g of the retractor-arm G. This retractor-arm has at its upper end a yoke g', which embraces an arm b⁵, and has across 95 its open end a bar g², on which a friction-roller g³ is mounted. This arm b⁵ is rigidly fastened to the casing B and has an eye b⁶, through which the trolley-cord p passes loosely. Around the shaft E one or more 100 coiled springs J are wound, one end of said springs being fastened to the hub g and the other ends to ratchet-wheels e, which are rotatably mounted on the shaft E. Pawls F,

pivoted to the frame members a' , engage with these ratchet-wheels and prevent them from turning backward under the influence of the said springs. These springs may be tightened 5 or wound up by turning said ratchet-wheels. The force of these springs is exerted, therefore, upon the retractor-arm in the direction to swing it rearward. Because of the described connections between said retractor-arm and the casing B the former cannot be so moved without also moving said casing. This movement of the casing is, however, prevented by a latch-lever K, pivoted to opposite sides of the casing and engaging with 15 catches formed by upward extensions a^8 of the two frame members a' . The forward end of this latch has a lifting-arm k , on which a friction-roller k' is mounted, and the latch is normally held in engagement with the said 20 catches, as shown, by a spring R, attached to the latch and engaging in a notch b^7 in the casing. The trolley-cord p passes under and engages with this friction-roller, and then passes through an opening in the casing to 25 the inclosed reel, to which it is attached.

Secured to the side d^3 of the reel are a plurality of strike-pins d^5 , which are parallel with its axis and are arranged systematically around the same, and on each of these pins 30 is a friction-roller d^6 . On the said side d^3 , near its periphery, is a series of ratchets d^7 , with which a pawl M is adapted to engage under certain conditions. This pawl is pivoted to the inside of the casing B above its 35 center when the casing is in its normal position, as shown, and this pawl tends to fall by gravity against an adjustably-fixed stop N, secured to said casing. Said stop N is pivoted to the casing, in which is a concentric 40 arch-shaped slot, and through this slot passes a screw, which may be screwed into the stop to fasten it to said casing. This pawl is provided with a strike projection M', which lies in the path of the rollers d^6 as the reel turns.

45 When the reel turns slowly, as it will so long as the trolley remains in contact with the conductor-wire, these pins lift the pawl slightly and pass under it; but when the trolley jumps from the wire and is pulled up 50 suddenly by its spring the reel is caused to rotate rapidly. In that event these pins on the reel hit the strike projection M' and throw this pawl violently outward, bringing its end into the path of the ratchets d^7 on said reel, 55 said outward movement being limited by the engagement of the end of the pawl with the flange b^3 . One of these ratchets d^7 engages with this pawl, and thereby locks the reel and casing together, so as to prevent their independent rotation. As soon as this result takes place the pull of the trolley upon the trolley-cord p causes said cord to lift the latch K, and thereby unlock the casing B from the frame A. Immediately thereafter the spring J of the 60 retractor-arm G swings said arm rearward. The casing necessarily turns with it until the parts assume the position substantially as

indicated by the dotted lines in Fig. 2, at which time the trolley has been pulled down until it is a considerable distance below the 70 planes of the conductor-wire or of its supporting-arms or cross-wires. The movement of the latch, induced by the pull of the trolley-cord, is limited by a finger b^8 , attached to the casing. (Shown in Fig. 2.) To replace 75 the trolley upon the conductor-wire, the attendant draws the trolley down still further by pulling upon its cord. He then turns the casing B and the retractor-arm E back to the positions shown in Fig. 2 and latches the casing to the frame. A slight backward movement of the reel relative to the casing releases the pawl M from the ratchet d^7 , whereby it may fall by gravity back against the stop N, in contact with which it normally lies, 85 and the parts are then in position to resume the operations described after the trolley has been caused to engage with the conductor-wire.

Attention is here called to the eccentric position of the axis of the retractor-arm, being, as shown, below and behind the axis of the casing. It is clear that as the retractor-arm is turned by its spring said spring loses its power, because it is unwinding, and it also 95 is obvious that as the trolley is pulled down the force of its spring is increasing, because it is being put under greater tension. In order, therefore, that it shall be unnecessary to provide a spring for operating the retractor-arm strong enough when partly unwound to move the trolley when the tension of its spring has been increased, the axis of said retractor-arm is placed as stated. As the 100 casing is turned backward the yoke upon the 105 retractor-arm moves out upon the arm b^5 away from its center of rotation, and thereby increases the leverage of said retractor-arm upon the casing more than enough to compensate for the decrease in force of the 110 retractor-spring and the increase in the force of the trolley-spring.

I claim—

1. In a trolley-retractor, the combination 115 of a frame, a member rotatively mounted thereon, mechanism exerting a force to turn said member in one direction, a latch which connects said member with said frame and prevents said turning, a reel rotatively mounted on said member, a spring acting to 120 turn said reel, the trolley-rope wound upon said reel and passing beneath said latch, ratchet-stops secured to said reel, a plurality of striker-pins also secured to said reel, and a pawl mounted on said rotatable member 125 and having a part which lies in the path of said pins, substantially as and for the purpose specified.

2. In a trolley-retractor, the combination 130 of a frame, a member rotatively mounted on said frame and having a guide-arm for the trolley-rope, an independently-rotatable reel, a spring tending to rotate said reel, mechanism adapted to be operated by the rapid

movement of the reel for locking it to the rotatable member, a spring-actuated retractor-arm pivoted below the axis of said rotatable member and having a sliding engagement with said guide-arm, and a latch adapted to hold said rotatable member against the pull of said retractor-arm, substantially as and for the purpose specified.

3. In a trolley-retractor, the combination of a frame, a casing rotatively mounted thereon and having a normally upwardly projecting arm on the end of which is a loop through which the trolley-rope passes, a reel concentrically mounted within said casing and adapted to wind up the trolley-rope, a spring tending to turn said reel, a series of ratchet-teeth, and a series of striker-pins secured to said reel, a pawl pivoted to the casing and lying between said pins and ratchets and projecting into the path of the former, mechanism exerting a force tending to turn said casing on its axis and a latch with which the trolley-rope engages for latching the casing to the frame against the force of said mechanism.

4. In a trolley-retractor, the combination of a spring-actuated rotatable reel, a series of striker-pins and a series of ratchets secured thereto, a pawl pivoted to an independent support and projecting into the path of said striker-pin, and a fixed stop with which said pawl normally contacts, substantially as and for the purpose specified.

5. In a trolley-retractor, the combination of a spring-actuated rotatable reel, a series of striker-pins and a series of ratchets secured thereto, a pawl pivoted to an independent support and projecting into the path of said striker-pin, and an adjustable stop with which said pawl normally contacts, substantially as and for the purpose specified.

6. In a trolley-retractor, the combination of a spring-actuated rotatable casing, an enclosed spring-actuated concentrically-mounted rotatable reel, mechanism operated by the sudden movement of said reel for locking the reel and casing together, and a latch-bar pivoted to the casing and adapted to engage with an immovable catch and having a lifting-arm under which the trolley-rope passes from the reel to the trolley whereby abnormal strains

upon the trolley-rope will raise said latch-bar, substantially as and for the purpose specified.

7. In a trolley-retractor, the combination of a rotatable member having a latch pivoted to said member and engaging with a fixed catch and having a lifting-arm under which the trolley-rope will pass, a spring-actuated retractor-arm pivoted eccentrically to said member and having at its free end a sliding connection with said rotatable member.

8. In a trolley-retractor, the combination of a rotatable member to which the trolley-rope may be attached, a guide-arm secured to said member having an eye through which the trolley-rope will pass; a latch pivoted to said member and engaging with a fixed catch and having a lifting-arm under which the trolley-rope will pass, a pivoted retractor-arm, a concentrically-mounted rotatable ratchet, a pawl preventing the backward movement of said ratchet, and a coiled spring secured at one end to said retractor-arm and at the other end to said ratchet, said retractor-arm having at its outer end a yoke through which said guide-arm loosely passes, substantially as and for the purpose specified.

9. In a trolley-retractor, the combination of a frame having two rearwardly-extended members, a casing having outwardly-projecting hubs which are rotatably mounted in said members, a shaft rotatably mounted in said hubs of the casing, a reel rotatably mounted upon said shaft, a helical spring secured at one end to said shaft and at the other end to said reel, means for turning said shaft independently of the casing, a device for locking said shaft and casing together, a spring, and intermediate mechanism whereby the spring exerts its force to turn said casing, a latch preventing the movement of said casing, which latch has a lifting-arm in the path of the rope passing from the trolley-pole to said reel, substantially as and for the purpose specified.

In testimony whereof I hereunto affix my signature in the presence of two witnesses.

ANDREW J. JOHNSON.
